CLAIM

The ornamental design for an ultraviolet detector as shown and described.

DESCRIPTION

1. Ultraviolet detector

1.1 : Perspective

1.2 : Perspective

1.3 : Front

1.4 : Back

1.5 : Left

1.6 : Right

1.7 : Top

1.8 : Bottom

1.1-1.8 are drawings showing an embodiment of the ultraviolet detector; the present product is used to test whether the sunscreen layer applied to the skin is even; the broken lines shown in the drawings illustrate portions of the ultraviolet detector and form no part of the claimed design.
